Primary Examiner — Philip S Hyder*Assistant Examiner* — Cary M Robinson(74) *Attorney, Agent, or Firm* — ScienBiziP, P.C.(57) **CLAIM**

The ornamental design for a display screen with graphical user interface, as shown and described.

DESCRIPTION

FIG. 1 is a front view of a first embodiment of a display screen with a graphical user interface showing the claimed new design; and,

FIG. 2 is a front view of a second embodiment of the display screen with the graphical user interface.

The broken line showing of the display screen is for the purpose of illustrating environment and forms no part of the claimed design. The broken line showing of elements on the display screen illustrates portions of the graphical user interface that form no part of the claimed design.

1 Claim, 2 Drawing Sheets
